(57) **CLAIM**

The ornamental design for a toothbrush head, as shown and described.

DESCRIPTION

FIG. 1 is a perspective view of the toothbrush head according to the new design;

FIG. 2 is a right side view, the left side being a mirror image thereof;

FIG. 3 is a front view thereof;

FIG. 4 is a rear view thereof;

FIG. 5 is a bottom view thereof; and,

FIG. 6 is a top view thereof.

FIGS. 1–6 show portions of the toothbrush head in phantom lines. The portions shown in phantom lines are for environmental purposes and form no portion of the claimed design.
